TELEPHONE TEST AND TALK-LINE MONITORING
SWITCH APPARATUS

Paul V. De Luca, Port Washington, and William V. Carney, Valley Stream, N.Y., assignors to Porta Systems Corp., Roslyn, N.Y.

Filed Mar. 29, 1972, Ser. No. 239,402

Term of patent 14 years

Int. Cl. D14—03

U.S. Cl. D26—14 A

FIG. 1

FIG. 2

FIG. 3

FIG. 4

FIG. 5

FIG. 1 is a perspective view of the telephone test and talk-line monitoring switch apparatus embodying our new design;

FIG. 2 is a rear view of the apparatus depicted in FIG. 1;

FIG. 3 is a front view of the apparatus shown in FIG. 1;

FIG. 4 is a bottom plan view of the apparatus depicted in FIG. 1; and

FIG. 5 is a side view of the telephone test and talk-line monitoring switch apparatus depicted in FIG. 1.

We claim:

The ornamental design for a telephone test and talk-line monitoring switch apparatus, substantially as shown.
